DESIGN FOR A GEAR SHIFT LEVER HANDLE

Henry W. Hey, Richmond, Va., assignor to Automatic Shifters, Inc., Richmond, Va., a corporation of Virginia

Application August 10, 1938, Serial No. 79,221

Term of patent 14 years

To all whom it may concern:

Be it known that I, Henry W. Hey, a citizen of the United States and a resident of the city of Richmond, county of Henrico, State of Virginia, have invented a new, original, and ornamental Design for a Gear Shift Lever Handle, of which the following is a specification, reference being had to the accompanying drawing, forming a part thereof.

Figure 1 is a perspective view of the handle showing my new design,

Figure 2 is a top plan view of the same,
Figure 3 is a bottom plan view of the same,
Figure 4 is a side elevation of the same,
Figure 5 is an elevation of the inner end of the same, and
Figure 6 is an elevation of the outer end of the same.

I claim:

The ornamental design for a gear shift lever handle, as shown.

HENRY W. HEY.
